POROUS REFRACTORY DIAPHRAGM

Filed May 31, 1928

By his Attorney

Edmund G. Borden

UNITED STATES PATENT OFFICE

RUSSELL E. LOWE, OF NEW YORK, N. Y., ASSIGNOR TO DOHERTY RESEARCH COMPANY,
OF NEW YORK, N. Y., A CORPORATION OF DELAWARE

POROUS REFRACTORY DIAPHRAGM

Application filed May 31, 1928. Serial No. 281,819.

The present invention relates to gas burners and more particularly to porous refractory diaphragms for the surface combustion of gaseous fuels.

5 It has been proposed to force an explosive mixture of gas and air through a porous refractory diaphragm and to burn the explosive mixture in the outer layer of the diaphragm, causing the surface of the diaphragm to become incandescent but with substantially no flame. An apparatus for burning explosive gaseous mixtures according to the method just mentioned is disclosed in 10 Patent 1,223,808 Bone et al.

15 It has been found that there is a tendency for the combustion to work inward into the refractory diaphragm. This tendency is objectionable, not only for the reason that it decreases the temperature and brightness of 20 the outer or exposed surface of the diaphragm, but also because the high temperature zone is apt to work back sufficiently far to ignite the gas at the inner or rear face of the diaphragm, thereby causing an explosion. Various devices have been proposed for 25 preventing the retrograde movement of the zone of combustion just described and it has been found useful, among other expedients, to maintain the radiation from the outer

30 surface of the diaphragm at as high a rate per square inch as possible. Among the expedients or devices previously employed for producing a high rate of radiation from the outer surface of the diaphragm is that of 35 forming parallel grooves and ridges on the outer surface of the diaphragm. It has been found, however, that diaphragms having ribbed surfaces, such as those just mentioned, soon crack when used for surface combustion.

40 It is the principal object of the present invention to provide a porous refractory diaphragm for surface combustion having a high rate of radiation and which is free from cracking and breaking from thermally produced stresses.

The novel features of the present invention are pointed out in the appended claims. The invention itself, however, together with further objects and advantages, will best be understood from the following description 50 taken in connection with the accompanying drawing in which:

Fig. 1 is a cross section taken through a surface combustion burner apparatus having a porous refractory diaphragm according to 55 the present invention;

Fig. 2 is a plan view of the diaphragm illustrated in Fig. 1.

The thermal stresses in porous refractory diaphragms used for surface combustion 60 and provided with parallel grooves and ribs have always produced cracks extending transversely of the ribs. It has been found, according to the present invention, that the formation of thermally produced cracks in 65 the surface combustion diaphragm can be avoided by forming the diaphragm with two sets of parallel webs or ribs, the webs or ribs of one set extending transversely to those of the other.

70 Referring to the drawing more in detail, 10 is a porous diaphragm according to the present invention. Diaphragm 10 is illustrated as mounted in a casing 12, one face of the diaphragm being exposed to the atmosphere. 75 The exposed face of diaphragm 10 is indented as indicated at 14, 14, the indentations 14 being spaced at their outer edges so that the diaphragm has ribs or webs 16, 16 and 18, 18 extending across its face between the 80 indentations 14. Preferably the indentations 14 have the form of inverted pyramids and flare outwardly toward the exposed face of the diaphragm. The webs 16, 16 run parallel 85 forming one set of webs or ribs and the webs 18 also are parallel each to each, but extend transversely of the webs or ribs 16. Preferably the webs in the set numbered 16 run at right angles to those in the set numbered 18. 90 Preferably the indentations 14 are made as

small as can be satisfactorily molded so as to increase the radiating surface of the diaphragm to the maximum. It has been found that pyramidal indentations having a square base of about one-fourth inch on the side is the minimum size permitted by the present methods of molding known to the applicant.

The indentations preferably have an angle of 60° and therefore a depth of slightly less than one-fourth inch when they have square bases one-fourth inch on each side. It will be understood that the ribs of the diaphragm are somewhat diagrammatic in Fig. 1, the depth of the indentations 14 being exaggerated. It has been found that a diaphragm eight inches square, two inches thick from the outer face of the ribs to the inner surface of the diaphragm and having square pyramidal indentations a little less than one-fourth inch deep and one-fourth inch on the side is suitable, when properly combined and molded, for a rate of gas feed of 250 cubic feet per hour. The rate of feed of gas, of course, depends not only on the thickness of the diaphragm, but also on the gas pressure. In the example just given a gas pressure of ten inches of water is assumed. With the same diaphragm, namely one two inches thick and eight inches square, a rate of 360 cubic feet of gas per hour is attained at a gas pressure of sixteen inches of water. The amount of air used with the gas in the apparatus under discussion is such as to produce an explosive mixture and is preferably either exactly or close to the amount of air required for theoretically complete combustion. An air-gas ratio of 5:1 is suitable when city gas having a B. t. u. value of approximately 550 per cubic foot is used.

The diaphragm, according to the present invention may be of any suitable material and compounded and molded as desired within the limits of good practice. The prior patents to Bone, Wilson & McCourt Nos. 1,223,308; 1,223,248; and 1,223,249 contain directions for compounding and firing porous diaphragms suitable for use in connection with the present invention.

It is preferred, however, to use a porous refractory diaphragm formed in accordance with the invention disclosed in the co-pending application of Messrs. Brown, Bjorkstedt and Lowe and according to which the diaphragm is formed principally of zircon (zirconium silicate), a very refractory material and one highly resistant to the flow of heat. The zircon is preferably bonded with one-half per cent of precipitated ferric oxide, molded into briquettes, fired, crushed and screened, the greater per cent of the particles being of a fineness of between 20 and 40 mesh and having a porosity of approximately 30 per cent. The porous particles just mentioned are then used to form the body of a porous diaphragm by mixing with approxi-

mately 12% of native zircon which has been milled to pass a screen of 300 mesh. The aggregate of porous particles of from 20 to 40 mesh and the finely milled particles of 300 mesh are preferably bonded by 6% of phosphorous pentoxide P_2O_5 with sufficient ammonia to neutralize the acid. The mixture is tamped in a mold having an indented surface design and baked at 140° to 180° F. to remove water. In order to prevent the diaphragm from adhering to the mold, the mold should be painted with flexible collodion before the material is placed therein. Flexible collodion is collodion containing about 2% of castor oil. Following removal from the mold the diaphragm is finished by firing to 2600°-2700° F.

In the arrangement illustrated, the casing 12 is formed to provide a gas chamber 20 at the rear of the diaphragm 10 and the explosive mixture of air and gas is introduced into the chamber 20 through a pipe 22. Air under suitable pressure may be introduced into pipe 22 through pipe 24 and gas under suitable pressure may be introduced into pipe 22 through pipe 26. Pipe 24 contains valve 28 and pipe 26 contains valve 30 whereby the amount of air and gas in the explosive mixture may be proportioned as desired. It will be noted also that a packing 32 is inserted between the edge of diaphragm 10 and the adjacent casing to prevent leakage of gas between the diaphragm and casing.

While I have described a particular method of making a diaphragm, it will be understood that I do not limit myself to any particular method, but contemplate, as within the present invention, all diaphragms having fine pores therein for the passage of gaseous mixtures and having an outer indented surface, the surface indentations being separated by two sets of webs and the webs of one set intersecting the webs of the other at an angle. Preferably, however, the webs of one set are parallel and cross those of the other set at right angles.

Having thus described my invention, what is claimed as new is:

1. A surface combustion apparatus comprising a porous diaphragm having indentations in its front surface and two sets of webs on said surface, the webs of one set crossing those of the other at an angle, a gas chamber at the rear of said diaphragm and means for introducing combustible gas and oxygen into said chamber.

2. A porous diaphragm refractory for the surface combustion of fluid fuel having indentations on one face and having two sets of webs on said face, the webs of one set crossing those of the other at an angle.

3. A diaphragm as set forth in claim 2 and in which the indentations are of pyramidal form.

4. A diaphragm as set forth in claim 2 and

in which the intersecting webs form angles of 90 degrees.

5. A porous refractory diaphragm for the surface combustion of fluid fuel having pyramidal indentations in one face and having two sets of webs on said face, the webs of one set crossing those of the other at angles of 90 degrees.

10. A diaphragm as set forth in claim 2 and in which the webs of each set are parallel and cross each other at an angle of 90 degrees.

In testimony whereof I affix my signature.

RUSSELL E. LOWE.
